To all whom it may concern:

Be it known that Victor E. Sowers, Jr., a citizen of the United States, residing at Lima, in the county of Allen and State of Ohio, have invented a new, original, and ornamental Design for a Telephone Receiver Holder, of which the following is a specification, reference being had to the accompanying drawing, forming part thereof.

I claim:

The ornamental design for a telephone receiver holder, as shown.

VICTOR E. SOWERS, JR.
